UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

APPARATUS FOR DISCHARGING VERTICAL RETORTS.

1,093,936.

Specification of Letters Patent. Patented Apr. 21, 1914.

Application filed July 23, 1913. Serial No. 761,484.

To all whom it may concern:

Be it known that I, HEINRICH KOPPERS, a subject of the King of Prussia, and residing at Moltkestrasse 29, Essen-on-the-Ruhr, in Prussia, Germany, have invented a certain new and useful Improvement in Apparatus for Discharging Vertical Retorts, of which the following is a specification.

The invention relates to apparatus for discharging vertical retorts, the latter being either intermittently or continuously discharged.

In connection with horizontal retort ovens for producing coke and gas, it has been discovered that with high and narrow chambers which are only heated at the sides, the cakes of coke split in the center. If, now, the chambers of vertical gas producing ovens are so dimensioned that they correspond approximately with the usual shape of coking ovens, and most of the heat from the furnace is utilized to heat the sides of the chambers, the result will be that in these particular ovens the cake of coke will likewise divide in the center. This phenomenon is utilized for emptying the retorts by providing at the bottom of each retort a wedgeshaped splitting body, which supports the cake of coke, and splits the latter open along its central plane. Devices are also provided for forcing every cake to the left and right so that the cake of coke is able to slowly descend. The particulars, dimensions of the chambers and the method of heating them has another effect. With chambers of the usual cross sections, and when heating them on all sides, a layer of graphite forms on the sides of the retort and sets so firmly that it is impossible for it to automatically release itself. In the present case, however, owing to the extension of the walls of the retort and to the front walls not being heated, the layers of graphite automatically peel off and pass away while the oven is in operation.

The invention is illustrated in the accompanying drawing, in which—

Figure 1 is a longitudinal section of the oven and Fig. 2 is a cross section to a larger scale of an essential part of the invention.

Similar reference letters denote similar parts in all the figures.

The retorts *a*, arranged in pairs at the side of one another, have a cross section of approximately 450x2500 mm. They are pro-

vided with a common hopper *b* closed by an ordinary type of closure *c*. The gas collecting chambers of the retorts are connected to two receivers *d* and *e*. The heating of the vertical chambers is preferably effected in such manner that the heat is divided into two horizontal currents which remain so until they have passed through the lateral heat accumulators *a* and *o*, thus enabling the pressure to be regulated. *p* and *q* are the flues. It should however be understood that the application of the invention is not confined to this particular construction of oven and method of heating.

Pivoted underneath each retort *a* inside an extension *f* of the latter is a segmental body *g* which can be rocked about a pivot by means of a lever *h* and a rope or chain *i*. The body *g* splits open the cake of coke along its natural seam and forces it away to the left and right while simultaneously supporting the cake of coke. The bodies *g* are hollow, and may be water cooled, the hot water escaping through holes *r* formed in the apex *s* and thereby serving to cool the incandescent coke. The steam formed thereby either escapes upward with the gas into the receivers *d* and *e*, or it is decomposed while passing through the contents of the retorts. This method of quenching the coke with hot water prevents the coke from being completely saturated or drowned with water, the superfluous water being able to run away, and the steam entering the dividing seam insures the contents of the retort being penetrated and at the same time cooled.

The invention is not limited to the particular form of construction described and shown, various modifications being provided without departing from the spirit of the invention.

I claim:

1. Apparatus for discharging retorts of coke ovens comprising means for splitting the coke cake, and means for imparting a to and fro movement to said splitting means.

2. Apparatus for discharging retorts of coke ovens, comprising means for splitting the coke cake substantially along its central vertical plane to subdivide the cake into two sections, and means for moving the splitting means alternately against one and the other of said sections.

3. Apparatus for discharging retorts of coke ovens, comprising a water cooled hollow device for splitting the coke cake substantially along its central vertical plane, and means for oscillating said device.
4. A coke oven provided with a plurality of coking chambers, coke cake-splitting members located at the bottom of said chambers, and means for simultaneously imparting a to and fro movement to said members. 10
- HEINRICH KOPPERS. [L.S.]
